Primary Examiner—James R. Largen**Attorney, Agent, or Firm**—Herbert Dubno; Ronald Lianides**[57] CLAIM**

The ornamental design for a controller for bathroom fixtures, as shown and described.

DESCRIPTION

FIG. 1 is a perspective view taken from the front and right side of a controller for bathroom fixtures showing my new design;

FIG. 2 is a perspective view taken from the bottom, rear and left side thereof;

FIG. 3 is a front elevational view of a second embodiment thereof;

FIG. 4 is a perspective taken from the top, rear and right side of FIG. 3, the left side being a mirror image of the right side; and,

FIG. 5 is a bottom plan view of FIG. 3.

FIG. 1

FIG. 2

FIG. 3

FIG. 4

FIG. 5
